UNITED STATES PATENT OFFICE.

WILLIAM O. BUNNELL AND OWEN G. WILLIAMS, OF WILKES-BARRE, PENNSYLVANIA,
ASSIGNORS OF ONE-HALF TO QUINCY A. GATES AND ONE-HALF TO SAID BUNNELL,
BOTH OF WILKES-BARRE, PENNSYLVANIA.

ATTACHMENT FOR TELEPHONES.

1,253,191.

Specification of Letters Patent.

Patented Jan. 8, 1918.

Application filed January 8, 1917. Serial No. 141,248.

To all whom it may concern:

Be it known that we, WILLIAM O. BUNNELL and OWEN G. WILLIAMS, citizens of the United States, residing at Wilkes-Barre, in the county of Luzerne and State of Pennsylvania, have invented certain new and useful Improvements in Attachments for Telephones; and we do declare the following to be a full, clear, and exact description of the invention, such as will enable others skilled in the art to which it appertains to make and use the same.

This invention relates to improvements in attachments for telephones, particularly sanitary mouth piece coverings and the means for changing said covering from time to time.

The principal object of the invention is to provide means whereby a fresh sheet of antiseptic material may be pulled across the mouth piece of a telephone upon which the device is secured each time the telephone receiver is removed from its hook.

An additional object is to provide a simple constructed sanitary attachment which can be mounted upon practically any form of telephone.

With these and many other objects in view, the invention resides in certain novel features of construction, combination and arrangement of parts which will be hereinafter more particularly described and claimed and shown in the drawings wherein:

Figure 1 represents a perspective view of an ordinary desk telephone equipped with the improved sanitary mouth piece covering;

Fig. 2 is a vertical section on the line 2—2 of Fig. 3; and

Fig. 3 is a similar view on the line 3—3 of Fig. 2.

From the several figures of the drawings, it will be noted that the mouth piece covering is adapted to be carried by a pair of rollers which are journaled in a frame, the latter being clamped to the standard S of an ordinary desk telephone T. The mouth piece of the transmitter of this telephone is designated by the letter M, the telephone receiver bears the character R and is supported by the usual hook H.

The frame F consists of an upright portion 1 having a spring clamp 2 formed integrally therewith, said clamp being adjustably positioned on the standard S, and a

number of arms which carry the operating means of the device. One of these arms designated by the numeral 3 extends forwardly from the upper end of the upright portion 1 and carries the antiseptic roll, the material of which is spread across the mouth piece between a pair of rollers 4 and 5, the strip of material being pulled from the first mentioned roller 4 by the rotation of the roller 5. The lower ends of these rollers 4 and 5 are journaled in a bar 6, while the upper ends are similarly held in spaced apart relation in a bar 7.

The lower end of the feed roller 5 has a bevel gear 8 fixed thereto which is continually in mesh with a similar gear 9, the latter being keyed to a horizontal shaft 10. This shaft is journaled in a suitable bearing 11 carried by an additional portion 12 of the frame F. It will be noted that this horizontal shaft 11 extends rearwardly beneath the transmitter and at right angles to the strip of antiseptic material covering the mouth piece.

The rear end portion of the shaft 10, or the end remote from that from which the gear 9 is secured, has an escape wheel 13 keyed thereto, said wheel having a plurality of notches 13' in its periphery. The extreme rear end of the shaft 10 beyond the wheel 13 is journaled in a plate 14 rising from the portion 12 of the frame F. Between this plate 14 and the escape wheel 13 is positioned an ordinary spiral or clock spring 15, one end of which is attached to the shaft 10 and the other to the plate 14.

A locking member 16 is provided for co-operation with any one of said notches 13' to prevent the wheel from rotating when the spring 15 is wound up. This locking member is mounted upon one end of a horizontal lever 17 which is pivoted intermediate its ends to the frame F. A contracting spring 18 connected with the lever 17 and the plate 14 holds the locking member in engagement with one of the notches. From this description it will be seen that whenever the locking member 16 is released from the notches 13', the shaft 10 will be caused to rotate and that this movement will be transmitted to the feed roller 5 and cause the antiseptic material to wind on the same from the other roller 4. It is to be understood that the member 16 is held out of engagement with

the escape wheel 13 to allow a quantity of antiseptic material equal to the distance between the two rollers 4 and 5 to wind upon the roller 5 from the roller 4.

5 In order to release the locking member 16 at the proper time to permit the spring 15 to actuate the shaft 10 and the feed roller 5, a depending arm 19 is formed on the outer end of the horizontal lever 17. The position of this lever and the depending arm is such that when the receiver R is lifted from the hook H it will necessarily engage the lower end of said arm and thus rock the lever in a direction to release said locking member. As soon, however, as the receiver has been entirely removed from its hook and out of engagement with the arm 19, the spring 18 will return the locking member into engagement with the periphery of the escape wheel 13 so that it will engage one of the notches 13 and arrest the movement of the mechanism.

The operation of this mechanism is prevented when the receiver is returned to its hook by the provision of a hinged end 20 of the depending arm 19. This end 20 it will be noted can swing only in one direction, namely, inwardly, thus when the receiver is returned to its hook, said end 20 will be 30 swung to the position shown in dotted lines in Fig. 2.

It is believed that the operation of the device is readily evident from the several figures in the drawings but briefly described 35 and is as follows:—Assuming that the frame F carrying the operating mechanism and the rollers 4 and 5 have been correctly adjusted with respect to the receiver R, the end of the antiseptic strip which is wound upon 40 the roller 4 is fixed to the feed roller 5 and partially wound therearound. This strip of material which covers the mouth piece end will prevent the accumulation of disease germs thereon. The parts are now 45 in position to be operated by the user of the telephone, who, when he removes the receiver from the hook automatically sets the device in operation. As hereinbefore mentioned, such removal of the receiver causes 50 the upper end thereof to engage the end of the depending arm 19 and disengages the locking member 16 from one of the notches 13, a sufficient length of time to permit the spring 15, which has been previously wound 55 up to rotate the shaft 10 and the feed roller 5 to pull a new strip of antiseptic material from the roller 4 and wind it around the roller 5. This strip of material remains in place after the receiver has been returned 60 to its hook and until another person removes the receiver for further operation of the telephone.

These movements are repeated until all 65 of the material has been wound from the roller 4 upon the roller 5, and by this time

the spring 15 has been nearly completely unwound. In order to rewind the same, the end of the strip of antiseptic material which was formerly on the roller 4 is pulled until the entire strip has been removed from the 70 roller 5, said roller being rotated during this removal, the rotation thereof being transmitted to the shaft 10 and to the spring 15. A new roll of material may then be placed upon the roller 4 as hereinbefore 75 mentioned.

We claim:—

1. The combination with a telephone, of a sanitary device therefor comprising a frame secured to the telephone, a roller containing a strip of antiseptic material journaled in said frame, a feed roller also journaled in said frame, means to cause said feed roller to pull a quantity of antiseptic material across said telephone mouth piece, 85 and means for retaining said means in inactive position and including a member positioned to be engaged by the telephone receiver when the same is removed from its hook. 90

2. The combination with a telephone, of a sanitary device therefor comprising a frame secured to the telephone, a roller containing a strip of antiseptic material journaled in said frame, a feed roller also journaled in 95 said frame, and means to cause said feed roller to pull a quantity of antiseptic material across said telephone mouth piece, a locking member retaining said means in inactive position, and an arm extending from 100 said member in a position to be engaged by the telephone receiver when the same is removed from its hook.

3. The combination with a telephone, of a sanitary device therefor comprising a frame 105 secured to the telephone, a roller containing a strip of antiseptic material journaled in said frame, a feed roller also journaled in said frame, and means to cause said feed roller to pull a quantity of antiseptic material across said telephone mouth piece, a horizontal lever pivoted to said frame, a locking member on one end of the lever to hold the means in inactive position, and a 110 depending arm on the other end of the lever to be engaged by the telephone receiver when the same is removed from its hook. 115

4. The combination with a telephone, of a sanitary device therefor comprising a frame secured to the telephone, a roller containing a strip of antiseptic material journaled in said frame, a feed roller also journaled in said frame, and means to cause said feed roller to pull a quantity of antiseptic material across said telephone mouth piece, a 125 horizontal lever pivoted to said frame, a locking member on one end of the lever to hold the means in inactive position, and a depending arm on the other end of the lever to be engaged by the telephone receiver when 130

the same is removed from its hook, the end of said arm being hinged to fold in one direction.

5. The combination with a telephone, of a sanitary device therefor comprising a frame secured to the telephone, a roller containing a strip of antiseptic material journaled in said frame, a feed roller also journaled in said frame, and means to cause said feed 5 roller to pull a quantity of antiseptic material across said telephone mouth piece, a pinion on the end of said feed roller, a horizontal shaft journaled in said frame, a second pinion on the end of said shaft and in mesh with the first mentioned pinion, an escape wheel fixed to the shaft and having a plurality of notches on its periphery, means for rotating said wheel, a locking 10 member for engagement with any one of said notches, a horizontal lever pivoted on said frame, said locking member being carried by one end of said lever, said arm being in position to be engaged by the telephone receiver upon its removal from its hook, the end of said depending arm being 15 hinged to fold in one direction.

10. The combination with a telephone, of a sanitary device therefor comprising a frame secured to the telephone, a roller containing a strip of antiseptic material journaled in said frame, a feed roller also journaled in said frame, and means to cause said feed 10 roller to pull a quantity of antiseptic material across said telephone mouth piece, a pinion on the end of said feed roller, a horizontal shaft journaled in said frame, a second pinion on the end of said shaft and in mesh with the first mentioned pinion, an escape wheel fixed to the shaft and having a plurality of notches on its periphery, means for rotating said wheel, a locking 15 member for engagement with any one of said notches, a horizontal lever pivoted on said frame, said locking member being carried by one end of said lever, said arm being in position to be engaged by the telephone receiver upon its removal from its hook, the end of said depending arm being 20 hinged to fold in one direction.

15. The combination with a telephone, of a sanitary device therefor comprising a frame secured to the telephone, a roller containing a strip of antiseptic material journaled in said frame, a feed roller also journaled in said frame, and means to cause said feed 15 roller to pull a quantity of antiseptic material across said telephone mouth piece, a pinion on the end of said feed roller, a horizontal shaft journaled in said frame, a second pinion on the end of said shaft and in mesh with the first mentioned pinion, an escape wheel fixed to the shaft and having a plurality of notches on its periphery, means for rotating said wheel, a locking 20 member for engagement with any one of said notches, a horizontal lever pivoted on said frame, said locking member being carried by one end of said lever, said arm being in position to be engaged by the telephone receiver upon its removal from its hook, the end of said depending arm being 25 hinged to fold in one direction.

6. The combination with a telephone, of a sanitary device therefor comprising a frame secured to the telephone, a roller containing a strip of antiseptic material journaled in

said frame, a feed roller also journaled in said frame, and means to cause said feed roller to pull a quantity of antiseptic material across said telephone mouth piece, a pinion on the end of said feed roller, a horizontal shaft journaled in said frame, a second pinion on the end of said shaft and in mesh with the first mentioned pinion, an escape wheel fixed to the shaft and having a plurality of notches on its periphery, means for rotating said wheel, a locking 30 member for engagement with any one of said notches, a horizontal lever pivoted on said frame, said locking member being carried by one end of said lever, a depending arm on the other end of said lever, said arm being in position to be engaged by the telephone receiver upon its removal from its hook, the end of said depending arm being 35 hinged to fold in one direction.

35. The combination with a telephone, of a sanitary device therefor comprising a frame secured to the telephone, a roller containing a strip of antiseptic material journaled in said frame, a feed roller also journaled in said frame, and means to cause said feed 35 roller to pull a quantity of antiseptic material across said telephone mouth piece, a pinion on the end of said feed roller, a horizontal shaft journaled in said frame, a second pinion on the end of said shaft and in mesh with the first mentioned pinion, an escape wheel fixed to the shaft and having a plurality of notches on its periphery, means for rotating said wheel, a locking 40 member for engagement with any one of said notches, a horizontal lever pivoted on said frame, said locking member being carried by one end of said lever, a depending arm on the other end of said lever, said arm being in position to be engaged by the telephone receiver upon its removal from its hook, the end of said depending arm being 45 hinged to fold in one direction.

In testimony whereof we have hereunto 50 set our hands in presence of two subscribing witnesses.
